UNITED STATES PATENT OFFICE

HARRY L. MILLER, OF CHICAGO, ILLINOIS, ASSIGNOR TO PETTIBONE MULLIKEN COMPANY, OF CHICAGO, ILLINOIS, A CORPORATION OF DELAWARE

RAILWAY-SWITCH STRUCTURE

Application filed May 15, 1930. Serial No. 452,673.

My invention relates more particularly to switch structures of the type commonly used in street railway tracks and comprising a tongue switch member pivoted at its heel portion to swing into and out of switching position, and one of my objects is to provide a novel construction of means for preventing the upward displacement of the tongue at its heel portion, while permitting of the desired freedom of pivotal movement on the base structure with which it is associated.

Another object is to provide means for the purpose stated to the end that the parts of the structure will be subjected to minimum wear and the life of the structure prolonged; and other objects will be manifest from the following description.

Referring to the accompanying drawings:

Figure 1 is a plan view of a switch structure of the character above stated and constructed in accordance with my invention.

Figure 2 is a plan view of the pivoted switch tongue of the structure shown in Fig. 1.

Figure 3 is an edge view of the pivoted tongue of Fig. 2.

Figure 4 is an enlarged section taken at the line 4 on Fig. 1 and viewed in the direction of the arrow.

Figure 5 is an enlarged section taken at the line 5 on Fig. 1 and viewed in the direction of the arrow.

Figure 6 is an enlarged section taken at the line 6 on Fig. 1 and viewed in the direction of the arrow.

Figure 7 is an enlarged section taken at the line 7 on Fig. 1 and viewed in the direction of the arrow.

Figure 8 is an enlarged broken plan view of the heel portion of the pivoted tongue member of the preceding figures and the other adjacent parts of the switch structure.

Figure 9 is a section taken at the line 9—9 on Fig. 8 and viewed in the direction of the arrows.

Figure 10 is a section taken at the line 10—10 on Fig. 8 and viewed in the direction of the arrows.

Figure 11 is a broken plan sectional view

taken at the line 11 on Fig. 9 and viewed in the direction of the arrow.

Figure 12 is a plan view of a cover forming an element of the construction; and

Figure 13, a section taken at the line 13 on Fig. 11 and viewed in the direction of the arrow.

Referring to the illustrated construction of the switch device, it comprises a base member 14 which may be, and preferably is, formed as an integral structure, as for example of manganese steel, this base member being provided at one end with a projection 15 in the form of a grooved rail section, the groove of which for receiving the wheel flange is represented at 16 and its running surface at 17. The body portion 14 at its opposite end is provided with two divergent portions 18 and 19 each in the form of a grooved rail section, the grooves in these sections being represented at 20 and 21, respectively, and their running surfaces at 22 and 23, respectively.

The body portion 14 is formed on its upper surface with a recess 24 in which the pivoted tongue member of the switch represented at 25 is located and in which it is shiftable back and forth about its pivot, the tongue member 25 being recessed lengthwise as represented at 26.

The body portion 14 is provided with a running surface 27 which connects the running surfaces 17 and 23, the running surface of the tongue 25 being represented at 28 and spanning the space between the running surfaces 17 and 22.

It may be stated that with the tongue member 25 in the position shown in Fig. 1 a car passing along the switch construction will travel continuously along the straight track, namely, along the running surfaces 17, 28 and 22. If a car approaches the tongue member 25 from the right in Fig. 1 over the switch track rail portion 19, the flange of the wheel wedges in between the portion of the base 14 presenting the running surface 27, and the tongue member 25, thereby swinging this tongue member in clockwise direction in Fig. 1 out of the way so that the car will pass

70

100

from the running surface 27 onto the straight track portion 15.

When the tongue member 25 is rotated on its pivot in clockwise direction in Fig. 1, the pointed end of the tongue member moves into the portion 29 of the recess 24 and this tongue member thus serves to force the wheels of an eastbound car moving along the track portion 15 toward the right in Fig. 1 to compel the car to travel along the running surface 27 thus switching it onto the switch track 19.

It will be understood that, in accordance with common practice, the side of the track opposite that at which the switch construction described is located may, or may not, contain a similar switch construction, and where it does not, the switch rail paralleling the portion of the base 14 provided with the running surface 27 and the rail portion 19 would converge toward the straight track rail, with its pointed extremity spaced from the straight track rail a distance sufficient to permit the flange of the wheel to continue along the straight track when the switch device is out of switching position, but to become engaged by the flange of the wheel when the switch device is shifted to switching position, in which case the switch device would operate to force the wheels to take the switch.

Referring now to the details of the pivoting of the tongue member 25 in place on the base 14, the base 14 contains an upwardly opening circular recess 30 in which the circular disklike heel portion 31 of the tongue member 25 is rotatable about a vertical axis, the wall of the recess 30 being cut away at its left-hand side in Fig. 1 to permit the tongue member 25 to occupy this recess and avoid obstruction to the tongue member in its swinging movements above referred to.

The bottom of the recess 30 represented at 32 contains an opening 33 therein which communicates with a cored out space 34 in the member 14 of larger dimensions than the opening 33.

The heel portion 31 of the tongue member 25 is provided, substantially coincident with the axis about which it rotates in the recess 30, with a depending lug 35, this lug presenting a spherical surface 36 at which it is engaged by similar spherical surfaces 37 and 38 provided on members 39 and 40 supported on the base member 14. The member 40 is shown as a head of a bolt 41 and the member 39 as a block through which the bolt 41 extends, the block 39 being slidable on the bolt. A coil spring 42 surrounds the shank of the bolt 41 and is held in compressed condition between the block 39 and a nut 43 screwed upon the threaded end of the bolt 41. The bolt 41, with its block 39 and spring 42, is mounted in the space 34 and is confined against upward displacement and displace-

ment to the left in Fig. 9 by fitting at its head 40 and block 39 within the confining walls of the space 34 as shown in Fig. 9, the spring 42 serving to force the parts 39 and 40 toward each other and in close engagement at their spherical surfaces 37 and 38 with the spherical surface 36 of the lug 35 thereby exerting pressure against the lug 35 in a direction to the right in Fig. 9 which presses the heel 31 of the tongue member 25 at its portion indicated at 44 against the portion 75 of the wall of the recess 30 indicated at 45.

Any tendency of the tongue member 25 to rise at its heel portion 31 is resisted by the engagement of the overhanging spherical 80 portions 37 and 38 of the members 39 and 40 with the spherical surface 36 of the lug 35.

The space 34 in the base member 14 is open at its top at one side of the heel 31 of the tongue member 25, this space being closed 85 by a removable and replaceable cover 46 formed with depending ribs 47 and 48, the two intermediate ribs 48 being spaced sufficiently closely together to prevent the nut 43 which extends between them, from accidentally rotating out of adjusted position.

While I have illustrated and described a particular construction embodying my invention, I do not wish to be understood as intending to limit it thereto as the same may be variously modified and altered without departing from the spirit of my invention.

What I claim as new, and desire to secure by Letters Patent, is:

1. A switch structure comprising a base member, a pivoted switch tongue member, and ball and sectional socket means on said tongue member and base member for preventing upward displacement of said tongue member.

2. A switch structure comprising a base member, a pivoted switch tongue member, ball and sectional socket means on said tongue member and base member for preventing upward displacement of said tongue member, and spring means forcing the sections of said socket into contact with said ball portion.

3. A switch structure comprising a base member, a pivoted tongue member, and means for holding said tongue member against upward displacement comprising a portion on said tongue member presenting a spherical surface and a plurality of relatively movable members having spherical surfaces at which they overlappingly engage the spherical surface of said tongue member.

4. A switch structure comprising a base member, a pivoted tongue member having a depending lug the outer surface of which is of arc-shape in plan and inclines toward the axis of rotation of said tongue member, and means for holding said tongue member against upward displacement comprising a plurality of relatively movable members

having surfaces at which they overlappingly engage said inclined surface of said lug.

5. A switch structure comprising a base member, a pivoted tongue member, and means for holding said tongue member against upward displacement comprising a portion on said tongue member presenting a spherical surface and a plurality of relatively movable members having spherical surfaces at which they overlappingly engage the spherical surface of said tongue member, and spring means forcing said last-named members into engagement with said tongue member.

10. A switch structure comprising a base member, a pivoted tongue member, and means for holding said tongue member against upward displacement comprising a portion on said tongue member presenting a spherical surface, a plurality of members having spherical surfaces at which they overlappingly engage the spherical surface of said tongue member, said last-named members being movable toward each other, and spring means urging said last-named members into engagement with said spherical surface of said tongue member.

15. A switch structure comprising a base member, a pivoted tongue member, and means for holding said tongue member against upward displacement comprising a plurality of members having surfaces at which they overlappingly engage said tongue member, a slidable rod carrying said last-named members, and a spring pressing against one of said last-named members and urging it toward the other thereof, said last-referred-to member being held on said rod against movement away from the other of said last-named members.

20. A switch structure comprising a base member, a pivoted tongue member and means for holding said tongue member against upward displacement comprising a portion on said tongue member presenting a spherical surface, a plurality of members having spherical surfaces at which they overlappingly engage the spherical surface of said tongue member, a slidable rod carrying said last-named members, and a spring pressing against one of said last-named members and urging it toward the other thereof, said last-referred-to member being held on said rod against movement away from the other of said last-named members.

25. A switch structure comprising a base member, a pivoted tongue member, and means for holding said tongue member against upward displacement comprising a plurality of members having surfaces at which they overlappingly engage said tongue member a slidable bolt the head of which constitutes one of said last-named members and the other of which is in the form of a block slideable along said bolt, and

a spring urging said block toward the head of said bolt.

30. A switch structure comprising a base member, a pivoted tongue member, and means for holding said tongue member against upward displacement comprising a portion on said tongue member presenting a spherical surface, a plurality of members having spherical surfaces at which they overlappingly engage the spherical surface of said tongue member, a slideable bolt the head of which constitutes one of said last-named members and the other of which is in the form of a block slideable along said bolt, and a spring urging said block toward the head of said bolt.

35. A switch structure comprising a base member, a pivoted tongue member, and means for holding said tongue member against upward displacement comprising a plurality of members having surfaces at which they overlappingly engage said tongue member, a slideable threaded rod carrying said last-named members, a nut on said rod and a spring located between said nut and one of said last-named members and urging the latter toward the other of said last-named members, said last-referred-to member being held on said rod against movement away from the other of said last-named members.

40. A switch structure comprising a base member, a pivoted tongue member, and means for holding said tongue member against upward displacement comprising a portion on said tongue member presenting a spherical surface, a plurality of members having spherical surfaces at which they overlappingly engage the spherical surface of said tongue member, a slideable threaded rod carrying said last-named members, a nut on said rod and a spring located between said nut and one of said last-named members and urging the latter toward the other of said last-named members, said last-referred-to member being held on said rod against movement away from the other of said last-named members.

45. A switch structure comprising a base member, a pivoted tongue member, means for holding said tongue member against upward displacement comprising a plurality of members having surfaces at which they overlappingly engage said tongue member, a slideable threaded rod carrying said last-named members, a nut on said rod and a spring located between said nut and one of said last-named members and urging the latter toward the other of said last-named members, said last-referred-to member being held on said rod against movement away from the other of said last-named members, said base member being recessed at the portion thereof at which said nut extends, and a cover for said recess containing a recess for receiving said nut and

holding it against rotation upon applying said cover to place.

14. A switch structure comprising a base member containing a recess, a tongue member located in said recess and having a rounded heel portion rotatable against a wall of said recess and a depending lug provided with an upwardly facing spherical surface, the bottom of said recess containing an opening therethrough and said base member containing a space with which said opening communicates and into which said lug extends, and means for preventing upward displacement of said tongue member comprising members having spherical surfaces overlappingly engaging said tongue member and confined in said space against upward displacement.

15. A switch structure comprising a base member, a pivoted switch tongue member, and means for holding said tongue member against upward displacement comprising a portion on said tongue member presenting an upwardly facing spherical surface and a portion on said base member presenting a downwardly facing spherical surface overlapping said spherical surface on said tongue member.

16. A switch structure comprising a base member, a pivoted switch tongue member, and means for holding said tongue member against upward displacement comprising a portion on said tongue member presenting an upwardly facing spherical surface and a plurality of portions on said base member each having a spherical surface overlapping the spherical surface on said tongue member.
